UNITED STATES PATENT OFFICE.

WILLIAM G. SCHAEFFER, OF READING, PENNSYLVANIA, ASSIGNOR TO
WILLIAM F. REMPPIS, OF READING, PENNSYLVANIA.

SADDLE-POST.

No. 815,475.

Specification of Letters Patent. Patented March 20, 1906.

Application filed August 19, 1905. Serial No. 274,953.

To all whom it may concern:

Be it known that I, WILLIAM G. SCHAEFFER, a citizen of the United States, residing at Reading, in the county of Berks and State of Pennsylvania, have invented new and useful Improvements in Saddle-Posts, of which the following is a specification.

This invention relates to improvements in adjustable seat-posts for cycles; and the object of the invention is to provide a pinch-binder for seat-posts of comparatively simple construction, one that will be positive in action, and neat in appearance.

My device dispenses entirely with the unsightly method of slotting the cycle-frame and fitting a clamping-bolt through the rear stays, as is usually done, this construction being troublesome in adjustment and weakening the parts.

My invention is fully described in the accompanying specification and clearly shown in the drawings forming a part hereof, in which—

Figure 1 shows a side elevation of a portion of a cycle-frame with my invention thereon. Fig. 2 is a plan view of the same with the seat-post removed.

The numeral 1 designates the frame, 2 the seat-mast tube, and 3 the top rail. In the top of the seat-mast tube I provide a slotted steel collar 4, having a flange 5 on its upper end.

The numeral 6 designates the binder-screw. This screw passes through the top

rail 3 of the frame in front of the seat-mast tube and comprises a bolt 6^a and a nut 7 on the opposite side of the frame. The screw is sufficiently long to engage the nut, and a movable block 8 is arranged on this pin or bolt. When the bolt is tightened up, the block 8 is drawn against the outer surface of the slotted collar 4 at one side, and the nut 7 is similarly drawn against said collar at the opposite side, thus causing it to firmly grasp the seat-post 9. The adjustment is simple and the parts easy of access.

Having thus fully described my invention, what I claim, and desire to secure by Letters Patent, is—

In a seat-post pinch-binder, a seat-mast tube, a slotted collar located in the top of said tube, a flange formed on said collar adapted to rest against the top edge of said tube, a square-headed screw entering the top rail of the frame immediately in front of said tube, a nut and a movable block on said screw said nut and block capable of being moved by the turning of said screw and adapted to contact with the outer surface of said slotted collar and cause it to firmly grasp the seat-post.

In testimony whereof I affix my signature in presence of two subscribing witnesses.

WM. G. SCHAEFFER.
